UNITED STATES PATENT OFFICE.

HARRY W. BOLENS, OF PORT WASHINGTON, WISCONSIN.

CRANK-CASING.

1,143,098.

Specification of Letters Patent. Patented June 15, 1915.

Application filed April 18, 1914. Serial No. 832,878.

To all whom it may concern:

Be it known that I, HARRY W. BOLENS, a citizen of the United States, and resident of Port Washington, in the county of Ozaukee and State of Wisconsin, have invented certain new and useful Improvements in Crank-Casings; and I do hereby declare that the following is a full, clear, and exact description thereof.

10 My invention has for its primary object to provide a simple, economical and convenient detachable crank-case for engines.

Specific objects of my invention are to provide a looped plate adapted to encircle 15 the crank-case having a flared end that is attached to the cylinder of the engine, its opposite end being supported by a transverse web of the engine bed; to provide a crank-case having one portion in the form 20 of a circular plate looped about the engine crank-shaft having a flared end that is secured to the engine cylinder, the opposite end of the loop being secured to a tray, which tray is tangentially disposed relative 25 to the loop end and removably supported within the bed of the engine, it being within the scope of my invention to connect the end loop of the plate to the engine bed in such manner that it constitutes a part or extension of a removable tray, the same being 30 supported by the engine bed above the floor line.

With the above and other minor objects in view the invention consists in certain 35 peculiarities of construction and combination of parts as set forth hereinafter with reference to the accompanying drawings and subsequently claimed.

In the drawings Figure 1 represents a sectional elevation of an engine bed and cylinder equipped with a crank-casing embodying the features of my invention, the section being indicated by line 1—1 of Fig. 2, and Fig. 2, a plan sectional view of the same, the 40 section being indicated by line 2—2 of Fig. 1.

Referring by characters to the drawings, 1 represents an engine bed of any desired type, provided with a cross-web 2 at its crank-shaft supporting end, the upper 45 stretch of said engine bed being formed with one member 3 of a journal-box, into which journal-box is mounted the crank-shaft of the engine, as indicated by dotted lines in Fig. 1. The opposite end of the bed carries the ordinary type of water-jacketed cylinder 5, which, in this instance, is shown as

an integral part of said bed. The bed is also provided with transversely extended lugs 6, which lugs constitute supports for the rear end of a removable drip-pan in the form of a tray 7, the said drip-pan being provided with upturned end and side walls, whereby oil thrown off from the working parts of the engine is trapped, the said tray being extended from end to end of the bed, 60 as shown. Secured to that end wall of the tray disposed under the crank-shaft, is a downturned flange 8 of a circular looped shield 9, the said flange 8 being riveted or otherwise permanently attached in this exemplification of my invention, to the tray end. The tray is of such length between its end flanges as to fit comparatively snug 65 between the cross-web 2 of the engine-bed and a transverse apron 2' at the other end of said engine bed, whereby said tray is held against end play. The rear end of the tray is supported by the lugs 6 upon which said tray loosely rests and the front or crank-shaft end of the tray is supported by the 70 circular shield plate which rests upon the upper face of the cross-web, the juxtaposed end of said tray being disposed below the top face of the cross-web, whereby lateral movement of the aforesaid tray is prevented 75 in one direction, while lateral movement in the opposite direction is checked by the apron 2'. As best shown in Fig. 2, the circular shield-plate extends upwardly and about the crank-shaft axis in somewhat 80 spiral form, whereby clearance of the crank-shaft oil-cup is had, which oil-cup, as shown in dotted lines, is attached to the engine pitman. The upper end of the circular shield 85 is flared toward the mouth of the cylinder 5 and terminates with an aperture 9' for the reception of a retaining member, which member, in this instance, constitutes the threaded end 10 of the cylinder oil-cup 10'. By this connection simplicity in construction is had, whereby the shank of the oil-cup serves as the permanent attaching member of the circular crank-shield. 90

From the foregoing description it is apparent that the shield and its permanently 105 attached tray can readily be removed or assembled with relation to the engine by manipulation of the retaining member, which, in this instance, is, as stated, the shank of the cylinder oil-cup that supplies 110 the cylinder.

While I have shown and described the

circular shield portion of the crank-casing as being provided with a downturned flange which is riveted to one of the end walls of the tray, it is obvious that I may, 5 without departing from the spirit of my invention, in some instances, support the tray independently of the shield portion. It is also within the scope of my invention to form the circular portion of the crank 10 case and the tray portion in one piece without departing from the spirit of my invention.

I claim:

1. An engine crank-casing comprising a 15 circular plate portion adapted to be looped about the engine crank having a flared securing end, and a removable vertical tray portion constituting a tangential extension of the other end of the looped portion.

20 2. A crank-casing for engines comprising a circular plate portion having a flared securing end and a removable vertical tray portion having upturned side and end walls, one of which end walls is secured to the 25 other terminal of the looped plate.

3. In an engine having a hollow bed provided with crank-shaft journal boxes, and a cylinder supported by the engine bed; the 30 combination of a two-part crank-shaft shield comprising a circular plate portion arranged about the crank-shaft axis, one end of which is flared toward the engine cylinder, means for securing said flared end to the engine cylinder, a tray portion secured to the other end of the circular shield portion, and means carried by the bed for supporting the tray.

4. In an engine having a hollow bed provided with crank-shaft journal boxes, a cylinder supported by the engine-bed, a web 40 extending across one end of said engine bed, and tray-supporting means carried by the opposite end of said engine bed; the com-

bination of a two part removable circular shield disposed about the crank-shaft journal-boxes of the engine bed having a flared end extending toward the engine cylinder, means for securing said flared end to the engine cylinder, the opposite end of the shield being engageable with the engine bed 45 cross-web, a flange extending from the last mentioned end of the circular shield, a tray portion secured to said flange having its opposite end in engagement with the tray-supporting means.

5. In an engine bed having a cylinder, a supporting base therefor provided with an end cross-web and a transverse apron, and lugs extending from the opposite walls of the bed; the combination of a two part removable crank-shaft shield comprising a circular portion arranged about the axis of the crank-shaft having a flared end secured adjacent to the mouth of the cylinder, a tray portion secured to the opposite end of the circular plate portion, the said tray portion being fitted between the cross-web and apron having one end supported by the lugs and its opposite end supported by engagement of the circular plate with the upper 55 face of the cross-web.

6. A two part crank-casing comprising a horizontally disposed drip-pan portion having a separable circular plate portion extending from one end of said drip-pan portion, the plate being provided with a flare at its opposite end for attachment to the engine.

In testimony that I claim the foregoing I have hereunto set my hand at Port Washington in the county of Ozaukee and State 75 of Wisconsin in the presence of two witnesses.

HARRY W. BOLENS.
